US00D800440S

(12) **United States Design Patent** (10) **Patent No.:** **US D800,440 S**
Shinga et al. (45) **Date of Patent:** **** Oct. 24, 2017**

(54) **SOCK**

(71) Applicants: **OKAMOTO Corporation**,
 Kitakatsuragi-Gun, Nara (JP); **Goto
 College of Medical Arts and Sciences**,
 Yokosuka, Kanagawa (JP)

(72) Inventors: **Ichiro Shinga**, Kitakatsuragi-Gun (JP);
Masahiro Sawada, Osaka (JP);
Kayoko Sato, Shinjuku-ku (JP);
Sawako Anada, Shinjuku-ku (JP)

(73) Assignees: **OKAMOTO CORPORATION**,
 Kitakatsuragi-Gun (JP); **GOTO
 COLLEGE OF MEDICAL ARTS
 AND SCIENCES**, Yokosuka (JP)

(**) Term: **15 Years**

(21) Appl. No.: **29/549,506**

(22) Filed: **Dec. 22, 2015**

(30) **Foreign Application Priority Data**

Jul. 29, 2015 (JP) 2015-016889
